E. SCHNEIDER

FASTENING DEVICE FOR GAS MAIN SWEAT PLUGS

Filed March 13, 1922

Inventor:
Edward Schneider
By Fischer & Fagaard
His Attorneys.

UNITED STATES PATENT OFFICE.

EDWARD SCHNEIDER, OF ST. PAUL, MINNESOTA.

FASTENING DEVICE FOR GAS-MAIN SWEAT PLUGS.

Application filed March 13, 1922. Serial No. 543,297.

My invention relates to fastening devices for gas main sweat plugs and has for its object to provide a device adapted to prevent the removal of the sweat plug from a gas main so that gas cannot be tapped from the main at this point and diverted from passing through the meter.

Another object is to provide a pair of hinged members adapted to surround the end of the **T** and the plug screwed therein with an annular groove adapted to fit around the bead of the **T** to prevent removal of the device when the members are held together.

A still further object is to form the members with rectangular notches in the faces thereof through which the plug is adapted to be passed to hold the device in normally upright position.

The full objects and advantages of my invention will appear in connection with the detailed description thereof and are particularly pointed out in the claims.

In the drawings illustrating the application of my invention in one form:—

Fig. 1 is a sectional view of a portion of a gas main showing the sweat plug with my invention attached thereto.

Fig. 2 is a side elevational view of the device shown in Figure 1.

In the connecting of the gas meter and service to gas mains the pipe is run along the ground which enters the building through the basement thereof shortly above the floor. Where this pipe comes into the building a riser is attached on which the meter is set. In order to drain the moisture and other condensation which may collect within the system a sweat plug is screwed into the **T** connecting the main and the riser. It is very frequently the case that unscrupulous people will unscrew the plug and tap gas off from the main at the **T** on which the riser is placed thereby diverting the gas from passing through the meter and utilizing the commodity of the gas company without cost. My invention prevents the theft of gas in this manner by locking the sweat plug in place so that the same cannot be removed without breaking the seal attached thereto.

In the drawings I have shown a horizontally positioned pipe 10 representing the gas main or supply pipe leading into the building. To this pipe is screwed a **T** 12

facing upwardly which **T** has screwed into it a riser 13 on which the gas meter not shown in the drawings is usually positioned. An ordinary plug 14 is screwed into the other branch of **T** 12 and serves as the sweat plug for the system to be used for draining and cleaning the riser 13 and pipe 10 from any condensation which may accumulate within the same.

My invention proper consists of two semi-circular members 15 and 16, which are each formed with an interior cavity 17 adapted to fit over the end of a **T** 12. The interior surface of these members is further formed with annular grooves 18 extending around the periphery of the same, which grooves are adapted to snugly fit around the bead of **T** 12 which is indicated in Figure 1 at 19. When the two members 15 and 16 are placed together the same occupy the relative positions shown in Figure 2. Each of these members is further provided with a rectangular notch 20 formed on the face of the same which is adapted to fit over the protruding end of a plug 14 so as to firmly hold the parts in upright position when the device is in place as indicated.

For fastening the device in place as indicated the members 15 and 16 are formed with leaves 21 and 22 cast integral therewith, which are riveted together at 23 to provide a hinge. Directly opposite the leaves 22 and 21 I form the same with two lugs 24 and 25 having registering holes 26 and 27 directly passing through the same. When the device is assembled a seal such as indicated at 29 having a wire 30 connected therewith may be used for sealing and securing the ends of said members 15 and 16 together by passing said wire through the holes 26 and 27 and then through the body of the seal proper so that the said wire may tightly draw together lugs 24 and 25 and hold the parts from movement.

It can readily be comprehended that when the device is applied the same cannot be removed without breaking the seal. As the plug 14 or either of these members are caused to rotate the groove 18 is caused to bear upon bead 19 which will tend to spread the members 15 and 16 apart and to break the seal, or to entirely arrest the movement of the same. If, on the other hand, the plug 14 is sufficiently forced into the **T** 12 and the members 15 and 16 turned relative to the

plug then the said members are caused to spread apart due to the formation of the notches 20 and the relation of the same to the end of the said plug. It can therefore be seen that irregardless of the manner of manipulation, the plug 14 cannot be removed from the T 12 when my invention is applied thereto without breakage of the seal 29.

The advantages of my invention are manifest. The device is extremely simple in construction and is absolutely positive in action so that the removal of the sweat plug from the gas main is effectively prevented. The device remains in an upright position at all times so that the reader of the meter can always inspect the seal to see that the same has not been broken or tampered with.

In accordance with the patent statutes I have described the principles of operation of my invention, together with the apparatus which I now consider to represent the best embodiment thereof, but I desire to have it understood that the construction shown is only illustrative and that the invention can be carried out by other means and applied to uses other than those above set forth within the scope of the following claims.

I claim:

1. In combination with a T having a bead, and a plug screwed therein, enclosing means comprising a pair of sections hingedly connected together and formed with an annular portion and a back portion, a groove positioned along the interior of said annular portion adapted to engage said bead, and notches formed in said back portions through which the head of said plug may be projected and means for securing said sections together.

2. In combination with a T having a bead and a plug formed with a square head screwed therein, enclosing means comprising a pair of sections hingedly connected together and formed with an annular portion and a back portion, said sections being open at their sides opposite the back portion, a groove positioned along the interior of said annular portion adapted to engage said bead, and angular notches formed in said back portions through which the head of said plug may be projected and means for securing said sections together.

In testimony whereof I affix my signature.
EDWARD SCHNEIDER.
